MACHINE FOR MAKING PILE DRIVER PADS

Anthony R. Sabellico, New Haven, Conn.

Application December 6, 1957, Serial No. 701,245

3 Claims. (Cl. 153—64)

This invention relates to improvements in pile driver pads, and particularly to a machine for making pile driver pads.

It is known in the art that, when driving concrete piles into the ground by means of a pile driver, it is necessary to interpose a resilient pad between the top of the pile and the hammer of the pile driver to take the impact and thereby protect the end of the pile from disintegration. One of the customary methods of making such resilient pads is to cut a steel cable into short lengths, equal or less than the diameter of the pile, and form a layer of these pieces, preferably joining adjacent pieces of cable by welded spots, then, repeating this process until several layers are formed, one above the other, the cable pieces of the adjacent layers being displaced at 90 degrees.

One of the important objects of my invention is to provide a resilient pile driver pad coiled from steel cable which has a longer life and which can be manufactured at a lower cost than the pile driver pads of the prior art.

Another important object of my invention is to provide a machine which makes it possible to manufacture such resilient pads coiled from steel cable, or from cable made of other suitable material, speedily, conveniently, and very economically.

Other objects and advantages of my invention will be apparent during the course of the following description.

In the accompanying drawing, forming a part of the present application, wherein for the purpose of illustration is shown a preferred form of my invention,

Figure 1 is a frontal elevational view of my machine,

Figure 2 is a partly sectional view of the same through the line 2—2 of Figure 1, showing also a partly completed coiled pad,

Figure 3 is a vertical sectional view of the same, with the tubular shaft in the raised position,

Figure 4 is a plan view of the coiled pad.

Referring to the drawing, the numeral 1 designates the base plate, which in the preferred form is rectangular in shape. This base plate has a central hole 2 and a circular guard 3, concentrically arranged. Secured to the base plate 1 are three legs 4, carrying the bearing 5, the bore of which is in alignment with the central hole 2. The circular guard 3 is interrupted in the front, as shown in Fig. 2.

Rotatably mounted in the bearing 5 and central hole 2 is the tubular shaft 6, the upper end of which is secured to a crank 7, and the lower end of which is provided with a slot 8. Secured to this tubular shaft 6, just above the slot, are the radial arms 9, which extend within a small clearance to the inner surface of the circular guard 3. Adjacent to the bearing 5 the tubular shaft 6 has a hole 10 containing a removable pin 11; in Fig. 1 the hole 10 and pin 11 are located adjacent to the lower end of the bearing 5, whereas in Fig. 3 by the axial shifting of the tubular shaft 6 the hole 10 and pin 11 are moved to the upper end of the bearing 5, thereby defining the two positions of the tubular shaft 6: the lower or normal position and the upper or discharge position.

An essential element of the machine is the knock out rod 12 located within the tubular shaft 6, as shown in Fig. 3. The upper end of this knock out rod 12 extends above the upper end of the tubular shaft 6, and is provided with a detachable cap 13, and a spring 14 interposed between the cap 13 and the upper end of the tubular shaft 6 to hold the knock out rod in position. When thus supported by the spring 14, the knock out rod 12 will have its lower end just slightly above the top of the slot 8 (see Fig. 3). When, however, downward pressure is applied on the cap 13 the knock out rod 12 will slide downwardly within the tubular shaft 6 forcing out any object located in the slot 8.

The operation of my machine is as follows:

Before starting the coiling of the pad the machine is properly anchored, preferably by bolts or screws passing through the anchoring holes 15 of the base plate 1. Then, the tubular shaft 6 is lowered into the normal position, shown in Fig. 1, and is locked in this position by inserting the pin 11 into the hole 10 located at the lower end of the bearing 5.

Following this, the end of the cable 16 is inserted into the slot 8 and the tubular shaft is rotated by means of the crank 7, feeding in the cable through the frontal gap 25 of the circular guard 3 (see Fig. 2). During this operation the coil of cable is kept within the circular guard 3 in a single layer by the radial arms 9 rotating with the shaft 6.

After the required length of cable has been fed in and the coil is tightly wound, the adjacent turns of the coil are secured to each other by welding at several points located between the radial arms 9. Then, the tubular shaft 6, together with the welded coil is raised into the position shown in Fig. 3 after the removal of the pin 11, and the shaft 6 is locked in this upper position by the insertion of the pin 11 into the hole 10 at the upper end of the bearing 5. Finally, downward pressure is applied on the cap 13 causing the knock out rod 12 to slide downwardly, against the spring pressure, forcing out the cable end from the slot 8 and thereby discharging the completed coil.

As the resilient pile driver pads usually made up of several of these coils placed one above the other, the above described operation will be repeated until the required number of coils are obtained.

It is to be understood that the form of my invention herein shown and described is only a preferred example of the same, and that various changes in the shape, size, and in the arrangement of the parts may be resorted to without departing from the spirit of my invention or the scope of the subjoined parts.

I claim:

1. A machine for making spiral pads of cable for use on the top of a pile to take the impact of the pile driver, comprising a base plate having a central hole and a concentric circular guard; a bearing aligned with said central hole and supported by legs secured to said base plate; a tubular shaft rotatable and sidable in said bearing and central hole, and having a slot at its lower end for receiving and engaging the end of a cable; said shaft having a hole enclosing a removable pin to secure said shaft in two positions, said hole and pin being adjacent to the lower end of said bearing in the normal position of said shaft, and adjacent to the upper end of said bearing in the raised position of said shaft; means for rotating said shaft to form a spiral coil of said cable; radial arms secured to said shaft and being so located that in the normal position of said shaft said arms will confine said spiral coil of cable within said circular guard and in a single layer; a knock out rod slidably mounted within

said tubular shaft and being adapted to force out the end of said cable from said slot of the shaft when said rod is moved downward within said tubular shaft.

2. The machine of claim 1 in which said knock out rod is supported by a spring resisting the downward movement of said rod and making it necessary to overcome the pres-

sure of said spring to move said knock out rod downwardly.

3. The machine of claim 1 in which said circular guard is interrupted for the convenient feeding in of said cable.
